(57) **CLAIM**

The ornamental design for a wheel for wheelbarrow or other implements that are manhandled, as shown and described.

DESCRIPTION

FIG. 1 is a three-dimensional view of a wheel for wheelbarrow or other implements that are manhandled showing my new design;

FIG. 2 is an axial view of the wheel for wheelbarrow or other implements that are manhandled of FIG. 1;

FIG. 3 is an opposite axial view of the wheel for wheelbarrow or other implements that are manhandled of FIG. 1;

FIG. 4 is a radial view of the wheel for wheelbarrow or other implements that are manhandled of FIG. 1;

FIG. 5 is another radial view of the wheel for wheelbarrow or other implements that are manhandled of FIG. 1;

FIG. 6 is a further radial view of the wheel for wheelbarrow or other implements that are manhandled of FIG. 1; and,

FIG. 7 is yet a further radial view of the wheel for wheelbarrow or other implements that are manhandled of FIG. 1.
